DONALD R. McCOWN AND MERCIDES VIVIAN MUMMA, OF SAN DIEGO, CALIFORNIA

SLEEPING HAIR NET

Application filed January 15, 1931. Serial No. 508,832.

Our invention relates to hair nets, more particularly to hair nets adapted to be worn when one is sleeping or merely reclining, and the objects of our invention are:

5 First, to provide a hair net of this class which cannot be dislodged or removed accidentally.

Second, to provide a hair net of this class which covers practically the entire head of 10 hair when the hair is arranged in a normal manner, whereby all parts of the head of hair are retained in place as long as the hair net is worn.

Third, to provide a hair net of this class 15 which though covering the entire head of hair allows a circulation of air around and through the hair so that the hair may readily dry, thus providing a hair net which is particularly adapted for use in setting the hair 20 after finger waves or other methods of training the hair have been used.

Fourth, to provide a hair net of this class 25 which is adapted to stretch slightly and thereby conform substantially to the irregularities of the hair.

Fifth, to provide a hair net of this class which is particularly simple and economical of construction and manufacture, there being but few parts and these being easily 30 formed.

Sixth, to provide a novel means and method of reinforcing the chin strap of a hair net of this class, and

Seventh, to provide on the whole a novelly 35 constructed hair net which is durable, efficient in its action, and which will not readily deteriorate or get out of order.

With these and other objects in view as 40 will appear hereinafter, our invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a front perspective view of the 45 hair net as it appears when worn;

Figure 2 is a rear perspective view as it appears when worn;

Figure 3 is a side elevational view of the net as it appears when worn;

Figure 4 is a perspective view of the net 55 as it appears in position for wearing;

Figure 5 is a reduced developed view of one of the top sections;

Figure 6 is a reduced developed view of 60 one of the side sections;

Figure 7 is a diagrammatical view showing the various sections of the net together;

Figure 8 is a fragmentary plan view illustrating the manner of constructing the chin 65 strap portion of the hair net; and

Figures 9 and 10 are diagrammatical views illustrating the process of forming the reinforcing chin strap.

Similar characters of reference refer to 70 similar parts and portions throughout the several views of the drawings.

Top sections 1, side sections 2, section connecting seams 3, chin strap reinforcements 4, securing snaps 5 and binding tape 6 constitute the principal parts and portions of our 75 hair net.

Two top sections 1 are provided which are substantially crescent shaped, being slightly wider at their central portions than at their ends, and each including a longer convex edge 80 1a, a shorter concave edge 1b, a front end 1c and a back end 1d. In addition to the two top sections 1, there are provided two side sections 2, each side section comprising a convex upper edge 2a, a concave front edge 2b, and a concave under edge 2c. The lower portion of each side section 2 is cut so that the front and under edges 2b and 2c form the margins of chin straps 2d.

The sections 1 and 2 are formed of netting or suitable gauze material which allows complete access of air to the hair.

The convex edges 1a of the two top sections 1 are joined together by a seam 3, which is formed as shown in Fig. 7, by doubling the margins of each section against itself and placing the margins so folded on top of each other so that the raw edges come within the margins of the seam, whereupon two rows of stitching are made firmly uniting the two sec- 100

tions. In a like manner, the concave edges 1b of the top sections are sewed to the corresponding side sections 2, forming other seams 3. When the four sections are thus 6 sewed together, a bonnet is formed, the lower edge of which extends horizontally around the neck approximately level with the chin, and the forward side of which extends across the forehead and down each cheek, as shown 10 best in the perspective views Figs. 1, 2 and 3; thus the hair when prepared as by a finger wave or the like may be completely covered, or practically so, and firmly held in place.

The chin straps 2d are adapted to extend 15 under the chin and into overlapping relation. Each chin strap 2d is provided with a reinforcing 4 which is formed of heavier material than the gauze used in the construction of the sections 1 and 2. The manner of securing this 20 reinforcing is substantially as follows:

The reinforcing is cut to the shape of the chin strap following the curvature of the section 2 until the margins of the chin strap merge into the body of the sections. The reinforcing 25 is first positioned as shown in Figs. 8 and 9 with its larger or root end adjacent the root of the strap 2d. The reinforcing is then sewed across its root and to the strap 2d. After the root end of the reinforcing 30 is sewed, it is doubled against itself by being folded along the seam formed by the stitching as shown diagrammatically in Fig. 10, in which position the margins of the reinforcing coincide with the margins of the 35 chin strap.

The front ends 1c of the top sections form a continuation of the front edges 2b of the side sections 2. This is also true of the back ends 1d which form continuations of the under 40 or back edges 2e of the side sections 2.

The edges of the hair net, after the several sections are sewed together, and the reinforcements are positioned, are bound with binding tape 6. The binding tape extends around the 45 margins of the chin straps, securing and covering the margins of the reinforcements 4 as shown in Fig. 4 and diagrammatically in Fig. 10.

After the binding is placed around the hair 50 net, suitable securing snaps 5, or other suitable securing means are secured to the two chin straps as shown in Fig. 4.

It is obvious that once the hair net is positioned and the chin straps are fastened, 55 that it is impossible for the hair net to shift so as to dislodge the arrangement of the hair, or to work off the head, thus the hair net is particularly adapted for use when one is lying down, whereby one may retain her hair 60 in the desired prepared arrangement when she is lying down.

Though we have shown and described a particular construction, combination and arrangement of parts and portions, we do not 65 wish to be limited to this particular construc-

tion, combination and arrangement, but desire to include in the scope of our invention the construction, combination and arrangement substantially as set forth in the appended claims.

Having thus described our invention, what we claim as new and desire to secure by Letters Patent is:

1. In a hair net, a pair of top members, each having a convex edge and an opposite concave edge, said top members being secured together by their convex edges, a pair of side members, each having a convex edge arranged to be secured to the concave edges of said top members, said top and side members being foraminous and together forming a bonnet structure, said bonnet structure being provided with angularly disposed intersecting openings, the margins of one of said openings fitting around the wearer's neck, the margins of the other of said openings fitting across the forehead and down the cheeks of the wearer, and securing means for said bonnet structure extending underneath the chin of the wearer.

2. In a hair net, a pair of top members, each having a convex edge and an opposite concave edge, said top members being secured together by their convex edges, a pair of side members, each having a convex edge arranged to be secured to the concave edges of said top members, said top and side members being foraminous and together forming a bonnet structure, said bonnet structure being provided with openings for receiving the face and neck of the wearer, and chin straps extending from said side members and arranged to overlap each other underneath the chin.

3. In a hair net, a pair of top members, each having a convex edge and an opposite concave edge, said top members being secured together by their convex edges, a pair of side members, each having a convex edge arranged to be secured to the concave edges of said top members, said top and side members being foraminous and together forming a bonnet structure, said bonnet structure being provided with openings for receiving the face and neck of the wearer, chin straps extending from said side members and arranged to overlap each other underneath the chin, a binding sewed around the margins of said bonnet structure, and said chin straps, reinforcing for said chin straps extending inwardly from the extremities thereof, and co-acting securing means mounted on each of said chin straps whereby said chin straps may be secured together.

4. In a hair net structure, a dome shaped head fitting member formed of netting, said head fitting member being open at its forward and lower sides, a pair of chin straps arranged to extend towards each other from opposite sides of the opening into said head

- fitting member, means for securing the extended portions of said chin straps together, whereby said opening into said head fitting member is divided into an aperture having 5 horizontal margins, and a second aperture having approximately vertically disposed margins, said apertures arranged to fit snugly around the neck and face respectively of the wearer.
- 10 5. In a hair net structure, a dome shaped, head fitting member formed of netting, said head fitting member provided with a pair of angularly disposed intersecting openings, the margins of said openings being approximately 15 mately at right angles, whereby the margins of one of said openings extend horizontally around the neck of the wearer, and the margins of the other of said openings extend approximately vertically across the forehead 20 and down the cheeks of the wearer, and chin straps at each side of said openings at their points of intersection, and means for connecting said chin straps together so as to separate said openings.
- 25 6. In a hair net, a plurality of section members formed of foraminous cloth of sufficient body to permit stitching, said section members sewed together along portions of their margins so as to form head fitting foraminous structure, said head fitting structure being provided with openings for the neck and face of the wearer.
- 30 7. In a hair net, a plurality of section members formed of foraminous cloth of sufficient body to permit stitching and shaped to conform substantially to portions of a person's head, said section members being stitched along portions of their margins so as to form a unitary head fitting structure.
- 35 8. In a hair net, a plurality of section members formed of foraminous cloth of sufficient body to permit stitching and shaped to conform substantially to portions of a person's head, said section members being stitched along portions of their margins so as to form a unitary head fitting structure, and a reinforcing member stitched around the margin of said head fitting structure.
- 40 9. In a hair net, a head fitting structure formed of foraminous cloth having sufficient body to permit sewing, said head fitting structure including a plurality of connected section members each conforming to a portion of a person's head.
- 45 55 55. In testimony, whereof we have hereunto set our hands at San Diego, California, this 9th day of January, 1931.

DONALD R. McCOWN.
MERCIDES VIVIAN MUMMA.
